ADJUSTABLE LOCK STRIKER PLATE

Glenn V. Searer, 3401 S. Nappanee St.,
Elkhart, Ind. 46514

Filed Oct. 31, 1972, Ser. No. 302,514

Term of patent 14 years

Int. Cl. D8—07

U.S. Cl. D8—117

Fig. 1

Fig. 2

Fig. 3

Fig. 4

Fig. 5

Fig. 6

FIG. 1 is a perspective view of an adjustable lock striker plate embodying the present design;

FIG. 2 is a front elevational view of the striker plate shown in FIG. 1;

FIG. 3 is an edge elevational view of the striker plate;

FIG. 4 is a rear plan view;

FIG. 5 is an edge elevational view opposite the view shown in FIG. 3; and

FIG. 6 is an elevational view of the end opposite the end shown in FIG. 1.

I claim:

The ornamental design for an adjustable lock striker plate, substantially as shown.
